EYELASH CURLER

Harold Aldritt Squire and Percy James Aldritt Squire, New Invention, near Wolverhampton, England; said Percy James Aldritt Squire assignor to Max Harry Greenman, London, England

Application January 4, 1938, Serial No. 183,368
In Great Britain October 8, 1937

3 Claims. (Cl. 132—32)

This invention relates to eyelash curlers actuated by a scissor-like action, and has for its object to provide an improved construction of such an article.

- 5 It has been proposed to construct an eyelash curler from a supporting lever having a finger loop at one end, and with the other end formed as two side bars at a distance apart, and to the ends of which was rigidly secured the fixed jaw 10 consisting of a curved strip of metal. An operating lever having a finger loop at one end and a cranked portion at the other end was pivotally connected to the supporting lever. A movable jaw consisting of a curved channel shaped member 15 having an india-rubber filling was slidably mounted on the side arms of the supporting lever and was connected to the cranked end of the operating lever by a wire of substantially V-shape or forked formation, so that by moving the finger 20 loop of the operating lever towards or away from the finger loop of the supporting lever, the movable jaw was moved on the side bars of the supporting lever to impart a sliding movement to the movable jaw in relation to the fixed jaw.
- 25 According to this invention, the movable jaw is free of the supporting lever, and is mounted on a member connected to the operating lever and to the supporting lever in such manner that the member is adapted to have a parallel motion 30 in relation to the supporting lever and the movable jaw a movement in a small arc of a circle or curve in relation to the fixed jaw.

The invention will be clearly understood from the following description aided by the accompanying drawing in which:—

35 Figure 1 is a side view of an eyelash curler according to this invention in the open position.

Figure 2 is a front view, and Figure 3 a plan of same, and

40 Figure 4 a similar view to Figure 1 but in the closed position.

According to the drawing, the eyelash curler consists of a lever 1 having a finger loop 2 at one end, and having the upper end bifurcated or provided with two rods 3, 3 which are spaced apart at their ends and to the ends is rigidly connected the upper jaw 4 which consists of a curved piece of thin metal. To the lever 1 is pivoted at 5 another lever 6 provided with a finger loop 7 at one end, this lever 6 being cranked or bent at a little distance from the pivot 5 as shown at 8. The end 9 of the lever projects beyond the pivot 5 for the required distance.

45 The lever 1 may be constructed from a single length of wire or rod suitably bent upon itself

and flattened at the adjacent parts for the pivot 5, and the lever 6 may also be formed from a single length of wire or rod suitably shaped upon itself and with the ends 9 flattened and passed through between the flattened portions of the 5 lever 1, the pivot 5 passing through holes in all the flattened portions.

The construction so far described is known, and according to the preferred form of the present invention, the lower jaw 10 which as is known 10 consists of a channel shaped curved metal strip in which is inserted a length of resilient material 11, is rigidly mounted on a member, consisting of a length of wire or rod, having a portion 12 of its length at the centre shaped to the curvature of the lower jaw 10, and to which portion 12 the lower jaw 10 is welded or otherwise secured. The wire on each side of the centre portion 12 is bent downwards, and curved forwardly and inwardly to form arms 13, 13, which at a 20 suitable distance from the portion 12 are brought nearly together and bent downwards to form straight portions 14 at a slight distance apart, said straight portions 14 being flattened and provided with two holes at a distance apart. 25

The flattened adjacent portions of the lever 1 is made longer than in the known construction and at a suitable distance below the pivot pin 5 is pivotally connected by a pivot pin 15 one end of a link 16, the other end of the link 16 30 being provided with a hole at the same distance from the pivot pin 15 as the hole in the end of the end 9 of the lever 6 is from the pivot pin 5.

The arms 13 are positioned through the arms 3 of the lever 1 and the end 9 of the arm 6 and 35 the end of the link 16 pivotally connected to the straight portions 14 by pivot pins 17, 18 passing through the holes in the end 9, link 16 and in the portion 14. The distance between the pivot pins 17 and 18 being the same as the distance between the pivot pins 5 and 15, so that the straight portion 14 is always parallel with the flattened portion of the lever 1 and with the lower jaw 10 under the upper jaw 4. 40

45 On opening the levers 1 and 6 by moving the finger loop 7 away from the finger loop 2, the lower jaw 10 is moved away from the upper jaw 4 as shown in Figure 1, and on moving the finger loop 7 towards the finger loop 2, the lower jaw 10 50 is moved towards the upper jaw 4 as in Figure 4.

By this invention, the lower jaw 10 is free of the arms 3 of lever 1, and by means of the parallel motion mechanism, the jaw 10 is moved in a small arc of a circle or curve in relation to the 55

upper jaw 4 and not by a sliding movement on the arms 3 of the lever 1 as is known.

Various other constructions can be employed without departing from the scope of the invention as defined by the following claims, for instance, two wires 13 without the connecting portion 12 could be employed, and the ends of the wires screwed, riveted or otherwise secured to the lower jaw 10, and the arms 13 can be, if necessary, connected together intermediate of their length by a cross-wire or strap. The lower jaw 10 may also be of other construction, such as a curved length of rod or bar covered with an india-rubber tube.

What we do claim as our invention and desire to secure by Letters Patent is:—

1. An eyelash curler incorporating a fixed jaw, a movable jaw, a supporting lever rigidly carrying the fixed jaw and an operating lever pivotally connected to the supporting lever for operating the movable jaw, characterised in that the movable jaw is free of the supporting lever and is mounted on a member connected to the operating lever and to the supporting lever, in such manner that the said supporting member is constrained to have a parallel motion in relation to the supporting lever, and the movable jaw a movement in a small arc of a circle or curve in relation to the fixed jaw.

2. In an eyelash curler incorporating a fixed jaw, a movable jaw, a supporting lever rigidly carrying the fixed jaw, and a cranked operating

lever pivotally connected to the supporting lever for operating the movable jaw, a curved member having a straight depending portion parallel with the supporting lever, the straight portion of the member being pivotally connected to the cranked end of the operating lever, a link pivotally connecting the straight portion of the member to the supporting lever at a distance from and parallel with the crank portion of the operating lever, and a movable jaw free of the supporting lever mounted on the upper end of the curved member, whereby the curved member is constrained to have a parallel motion in relation to the supporting lever, and the movable jaw a movement in a small arc of a circle or curve in relation to the fixed jaw.

3. An eyelash curler comprising a bifurcated supporting member having a curved jaw extending between and fixed at its ends to the forks thereof, a curved movable jaw of a shorter length than said fixed jaw to engage the latter, a reciprocating member on which said movable jaw is mounted independently of the forks of said supporting member, a parallel motion connection between said supporting and reciprocating members operative during reciprocation of the latter to guide the movable jaw for movement in an arcuate path to and from engagement with the fixed jaw, and an operating lever for said reciprocating member.
